Application September 11, 1939, Serial No. 294,237

16 Claims. (Cl. 171—327)

This invention relates to piezoelectric apparatus utilizing piezoelectric units for interconverting electrical and mechanical vibratory energy, and relates particularly to heated piezoelectric units used for the purpose of improving the operating characteristics of such apparatus.

It is known that piezoelectric units of the Rochelle salt type exhibit certain technical characteristics (described below in detail) which become especially objectionable under some conditions of use and which generally impair the use of such units in piezoelectric apparatus.

It is the primary object of this invention to provide a piezoelectric transducer assembly in which these objectionable features are substantially avoided.

It is another object of the invention to provide a transducer in which objectionable operating characteristics resulting from temperature variations are substantially avoided.

It is another object to provide a transducer assembly utilizing a heated piezoelectric unit.

It is another object to provide a transducer assembly having a heated piezoelectric unit combined with heated damping means.

It is another object to provide a piezoelectric motor device utilizing a heated piezoelectric unit in which overloading is prevented while the unit is being heated to its operating temperature.

Other objects will in part be obvious and will in part appear hereafter.

It has been found that piezoelectric materials of the Rochelle salt type exhibit a number of technical characteristics which vary with or are affected by temperature changes. Some of these characteristics change only to a small extent with changes in temperature while others change greatly, but it has been found that all of them are subject to rather abrupt and sharp changes when the temperature passes through either one of two critical ranges centered around temperatures known as the Curie points of the material. The Curie points are generally spaced apart somewhat in the temperature scale and for that reason are commonly referred to as the "upper" and "lower" Curie points. For example, the upper Curie point of Rochelle salt is commonly considered to be around 23.5° C., while the lower Curie point occurs at about -20° C. It will be apparent that in general, the lower Curie point of Rochelle salt is so far below the temperatures at which piezoelectric devices are ordinarily operated that it seldom needs to be given any consideration.

On the contrary, however, the upper Curie

point lies within the temperature range in which most devices are operated. Consequently, the abrupt changes in characteristics which occur in this upper critical temperature range may, and often do, occur while the device is in operation, causing unexpected and objectionable alterations in its performance. This is especially true of devices using unrestrained piezoelectric members. The bimorph type of piezoelectric unit wherein the piezoelectric material is restrained by other piezoelectric material or by non-piezoelectric material greatly reduces these undesirable characteristics, so much in fact, that they may be considered negligible for many applications. However, in other applications the remaining effects are of importance. Heretofore, little, if any, control could be exercised over these remaining objectionable effects in the bimorph or over the large effects observed in unrestrained plates (except by substituting bimorphs when possible) with the result that they have come to be regarded practically as inherent defects of piezoelectric materials which could not be avoided commercially by any practical means.

As intimated, however, this invention provides such commercially practical means and permits a high degree of control for both bimorph and unrestrained piezoelectric transducers.

The essence of this invention lies in the discovery that highly satisfactory performance may be obtained from a piezoelectric unit when it is heated to temperatures somewhat above the upper Curie point, and particularly when its temperature is held within a moderately restricted range lying somewhat above the Curie point. It has been found particularly that heating the piezoelectric unit to these temperatures affects each of the technical characteristics known as "sensitivity," "linearity," "creep," "hysteresis," and impedance; stabilizing sensitivity and impedance, improving linearity, and materially reducing creep and hysteresis.

By the term "sensitivity" is meant the deflection, per unit of applied voltage, of a chosen point on a piezoelectric unit. Speaking generally, the sensitivity of piezoelectric units at temperatures below the upper Curie point is at a high level, but changes gradually with temperature until the temperature enters the critical range centered around the Curie point. As the temperature passes through this range the sensitivity decreases very sharply, and then as the temperature rises above it, the sensitivity gradually becomes stabilized at a low level,

changing but slightly as the temperature increases further.

The term "linearity" expresses qualitatively a relation of direct proportionality between the deflections of a piezoelectric unit, and the corresponding applied voltages which produce those deflections. It will be understood that if there is direct proportionality between these values, then the sensitivity curve will be a straight line, and will be said to be linear. Perfect linearity in a piezoelectric unit is the ultimate desire since in terms of operation, it means that if the applied voltage is doubled, for example, the deflection of the unit will also be doubled. Furthermore, it is especially desirable that perfect linearity be exhibited over a wide range of applied voltages since then the same relative accuracy may be obtained from a device at high values of applied voltage as at low values, and the field of utility of the device will be correspondingly widened. It has been found that at temperatures below the Curie point, the relationship between deflection and voltage is non-linear, while at temperatures above the Curie point, the relationship is substantially linear.

"Creep" is a term used to describe an especially objectionable characteristic of piezoelectric materials. A piezoelectric unit exhibiting this phenomenon rapidly assumes an initial deflection when a voltage is applied to its terminals, but then it gradually creeps to greater deflections until it ultimately comes to rest at a maximum value. When the charge is removed from the unit, the same type of action reoccurs in the reverse direction. It has been found that this creep action attains greatest magnitude, and is therefore most serious, at temperatures below the upper critical temperature range, but is negligible at temperatures above the critical range.

"Hysteresis" in piezoelectric material is fully analogous to hysteresis in magnetic materials, the term being used to signify that the ultimate deflection of the unit lags behind the applied voltage when the voltages are applied in a reversed cycle. In terms of actual operation, if a unit is permitted to assume its ultimate deflection when a constant positive difference of potential is applied to its terminals, a greater negative difference of potential must be applied in order to restore the unit to zero deflection. Hysteresis has been found to occur to an objectionable extent in unrestrained piezoelectric material at temperatures below the upper Curie point, but to become negligible at temperatures above the Curie point.

The electrical impedance of a piezoelectric device varies markedly with temperature. In general, the impedance at any particular frequency first decreases as the temperature increases, reaching a minimum in the neighborhood of the upper Curie point; and then increases as the temperature is raised above the Curie point, increasing rapidly at first in the critical range, and then more slowly as the temperature is further increased. The advantage of operating the piezoelectric unit above the Curie point, in so far as impedance is concerned, lies in the fact that variations in impedance for any specified frequency are greatly minimized, especially if the temperature is maintained well above the Curie point. Stabilization of the impedance characteristic of the piezoelectric unit is desirable because it permits greater flexibility in circuit design, since the effect of the impedance in

the circuit will be essentially constant and therefore may be predicted.

From what has been said above, it will be understood that a piezoelectric unit heated to above the upper Curie point will exhibit negligible creep and hysteresis, especially good linearity, and stabilized sensitivity and impedance. However, a more comprehensive understanding of the improvements resulting from the use of a heated piezoelectric unit may be had through reference to a particular device embodying the invention, a pen recording device having been chosen for purposes of illustration.

Referring now to the drawings,

Fig. 1 is a plan view of a piezoelectrically-actuated pen recording device.

Fig. 2 is a front elevation of the device having portions thereof broken away to show interior features.

Fig. 3 is a sectional view taken on the lines 3, 3 of Figs. 1 and 2.

Fig. 4 is an exploded view of the heating unit employed in the device of Figs. 1 through 3.

Fig. 5 is a chart showing the effect of temperature on the sensitivity of a piezoelectric unit of the type used in the device of Figs. 1 through 3.

Fig. 6 is a chart showing the effect of temperature on the linearity of the response of a piezoelectric unit.

Fig. 7 is a diagrammatic representation of a test voltage applied to the device of Figs. 1 through 3.

Fig. 8 is a typical curve illustrating the manner in which the device of Figs. 1 through 3 responds to the test voltage of Fig. 7 when the temperature of the device is below the upper Curie point.

Fig. 9 is a response curve similar to that of Fig. 7, the temperature of the device being above the upper Curie point, but the adjustment of the damping unit of the device remaining unchanged.

Fig. 10 is a response curve similar to that of Fig. 8, the damping unit having been readjusted to produce optimum damping at the higher temperature.

Fig. 11 is a schematic diagram of a suitable circuit for the device of Figs. 1 through 3.

Referring now to Figs. 1, 2 and 3, the pen recording device comprises a piezoelectric motor assembly A actuating a motion-amplifying assembly B which carries a pen adapted to oscillate transversely back and forth across a paper strip C travelling longitudinally under the pen. A damping unit D is coupled to the motion-amplifying assembly B. Electric heating units E, E' supply heat to the piezoelectric motor and to the damping unit, and a thermostat F connected in circuit with the heating units E, E' controls the heating units to maintain the temperature of the device at a desired level.

The piezoelectric motor assembly A comprises a cup-shaped case 1 composed preferably of cast metal, the cavity in the case being closed by a metal cover plate 2 secured tightly to the case in a suitable manner as by means of screws 3, 3 and

clamping a pair of gaskets 4, 4 between the abutting surfaces of the plate and case. A square multiple-plate piezoelectric unit 5 of the bimorph type (such as described in U. S. Patent No. 2,105,011 granted to A. L. W. Williams, or U. S.

Reissue Patents No. 20,213 and 20,680 granted to C. B. Sawyer) is clamped at each of three corners between the cover plate and the base wall of the case, the piezoelectric unit being spaced from the case by rubber pads 6, 6 and from the cover plate by ball bearing supports 7, 7, of the type

described and claimed in the copending application of Alfred L. W. Williams, Serial No. 240,261, filed Nov. 18, 1938. The fourth and unclamped corner of the piezoelectric unit has a driving clamp 8 fitted therearound and secured thereto, a drive pin 9 being secured to the clamp and extending outwardly therefrom through an opening in the cover plate 2. The case 1 is provided with a contact strip 10 recessed in a side wall thereof and carrying four contact terminals designated 11, 11a, 12, and 12a. The electric leads of piezoelectric unit 5 pass between gaskets 4, 4, and are connected to terminals 11 and 11a. The heating circuit (described below, and comprising the heating units E, E' and thermostat F) is connected to the other terminals 12 and 12a. It will be understood that an alternating potential applied between terminals 11 and 11a causes piezoelectric unit 5 to vibrate in such manner that drive pin 9 is vibrated in an endwise direction.

The motion-amplifying assembly B is secured to and supported by a bracket 13 and comprises a spindle 14 which has two curved bearing surfaces of the same radius and another curved surface of slightly larger radius disposed between the two first-mentioned surfaces. The spindle is operatively supported by flexible tension members 15, 15 so that it may roll back and forth a small distance along the plane defined by those members. A similar flexible tension member 16 is frictionally mounted on the middle curved surface and connected to drive pin 9. A long hollow tube 17 terminating in a glass pen point 18 is secured to the top of the spindle, and is supplied with ink through tube 19 from ink-well 20. Due to the difference in length of the radii of the curved bearing surfaces and the middle curved surface, slight endwise motion of drive pin 9 in response to an applied electro-motive force between terminals 11 and 11a results in a relatively large angular motion of the spindle 14 and of the pen point 18.

In operation, a strip of paper C moves over roller 21 and table 22 under pen point 18. The pen point traces a graph on the moving paper of the electrical waves applied between the terminals. For a detailed description of the operation of this piezoelectrically actuated pen recording device, reference may be made to U. S. Patent No. 2,149,216 granted to Charles K. Gravley.

The damping unit D is of the tuned or frequency-selective type and comprises an elongated bar 23 of compliant and flexible damping material such as Viscoloid or other similar rubber-like material. The upper end of the bar 23 is secured to the lower end of the spindle 14, while the lower portion of the bar 23 is held in a clamp 24 secured to cover plate 2. Two metal discs 25 are frictionally retained at intermediate points along the bar 23, and may be adjustably positioned therealong so that their spacing from each other and from the upper end of the bar is effective in producing optimum damping at a desired frequency. The operation of this type of damping unit is described in detail and claimed in the copending application of A. L. W. Williams and Joseph J. Neff, Serial No. 240,260, filed Nov. 14, 1938, and reference is made to that application for a full disclosure of the damping unit shown here and of various modifications which may also be used.

The heating units E, E' are disposed adjacent the remote faces of the piezoelectric motor assembly A. Each unit consists of a flat helix of 75

resistance wire or ribbon 26 wound around a rectangular sheet 27 of insulating refractory material such as mica, the coils of the helix being spaced apart by fingers 28 extending outwardly between the ends of adjacent coils. The ends of the helix are connected to external lead wires 29, 29' by suitable means such as rivets 30, 30. Insulating sheets 31, 31 are secured to sheet 27 on opposite sides of the helix, the assembly being secured together at the top and bottom by suitable means such as rivets inserted through the holes 32, 32.

Heating unit E is disposed adjacent the outer face of the base wall of case 1 being surrounded by a gasket 33 having slightly greater thickness. An outer cover plate 34 protects the heating unit, the plate being secured to case 1 by means of screws. In order to hold the heating unit in spaced relation to gasket 33, and also to insulate the heating unit thermally from the outer cover plate 34, a compressible layer of insulating material 35 such as woven glass or asbestos cloth is placed between the outer surface of the heating unit and the inner surface of cover plate 34, its thickness being such that it provides the desired insulating effect and also presses firmly against the heating unit when the cover plate 34 is tightened against gaskets 33.

Heating unit E' is disposed adjacent the outer surface of cover plate 2, being surrounded on three sides by a U-shaped gasket 36 and being partially covered with thermally-insulating cloth 37. It is clamped in place and protected by a cover plate 38 which is secured by screws 39, 39 to case 1. This latter cover plate does not extend over the whole exposed surface of cover plate 2, the right hand portion, except the upper part forming bracket 13, being bent outwardly to form two walls 40 and 41 of a housing for the motion-converting assembly B and its attached damping unit D. A second bent plate 42 having a U-shaped section forms the top wall 42a, side wall 43, and bottom wall 44, the plate 42 being secured to wall 41 by means of screws 45, 45. A rectangular plate 46 closes the upper portion of the housing which lies directly below bracket 13. It will be seen that this assembly of plates forms a housing which substantially encloses the assembly B and damping unit D.

The thermostat F is of conventional construction, and since its structure forms no part of this invention, description of its internal features is omitted. Its action will be fully understood by those skilled in the art to which this invention relates. The thermostat is disposed within the housing around the damping unit, being clamped into the corner formed by walls 40 and 41 by means of a clamp 47, which is secured to wall 40 by means of bolt 48. The thermostat is connected in series circuit with heating units E and E', lead wire 29 of heating unit E' being connected to terminal 49 of the thermostat, lead wire 29' of heating unit E being connected to its other terminal 50. Lead wire 29' of heating unit E' is connected to terminal 12, and lead wire 29 of heating unit E is connected to terminal 12a. The thermostat is preferably of the adjustable type so that it may be set to open or close the heating circuit when the temperature within the housing rises above or falls below a desired value or restricted range of values. It will be recognized that the thermostat does not respond directly to the temperature of the piezoelectric unit 5 since it is spaced some distance away. It will also be recognized, however, that

the temperature gradient between the piezoelectric unit and the thermostat remains practically uniform over the range of temperatures which are ordinarily employed in the device. For that reason it may be necessary to adjust the thermostat to respond to a temperature somewhat different from the temperature which it is desired the piezoelectric unit should attain during operation, but once the adjustment has been made, the thermostat will thereafter maintain the piezoelectric unit at the desired temperature.

The structure of the device having now been described, it will be understood that when it is desired to operate the device, the electromotive force which it is desired to record is connected to terminals 11 and 11a, while a suitable source of heating current is connected to terminals 12 and 12a. After the piezoelectric unit 5 and damping unit D have attained their respective thermostatically-controlled temperatures, the recording device will trace an accurate record of the electromotive force connected to terminals 11 and 11a.

Some of the advantages which result in the pen-recording device from the use of a heated piezoelectric unit either by itself or in combination with a heated damping unit will be more apparent from a study of the curves shown in Figs. 5 through 10.

Fig. 5 is a graph showing the variation with temperature of the sensitivity of a piezoelectric unit of the type shown in Fig. 3 and designated by the numeral 5. The curve shows the deflections produced at various temperatures by a constant applied electromotive force of 50 volts. It will be noted that when the temperature of the unit is approximately 13° C., 50 volts applied to its terminals causes a deflection of approximately 6 units, while at 20° C. the same voltage produces a deflection of 8 units. The sensitivity continues to increase as the temperature rises until at approximately 23° C. (i. e., around the Curie point) it begins to decrease sharply with increasing temperatures, the decrease continuing at a high rate until the temperature of approximately 28° C. is reached. The sensitivity then again becomes more stable, decreasing only slightly with further increases in temperature. It will be noted that at approximately 30° C., 50 volts produces a deflection of about 2 units, from which fact it will be apparent that operation of the piezoelectric unit at temperatures above the Curie point results in marked reductions in sensitivity. This apparent disadvantage, however, is more than offset by the attendant improvements in operation with respect to linearity, creep, etc., as will be shown below.

The improvement in linearity obtainable by operation of a piezoelectric unit of the type shown in Figs. 1 to 3 at temperatures above the upper Curie point is clearly shown in Fig. 6, in which deflections are plotted against applied voltage, each curve in the group representing the relationship existing between deflection and voltage at the indicated temperature. At temperatures of 14° C. and 19° C. it will be noted that there is a relationship of approximate direct proportionality for voltages above about 25, but that the relationship is non-linear for lower voltages. At 23° C. the relationship between deflection and applied voltage is extremely non-linear, while at 28° C., there is a linear relationship up to voltages of about 250, the relationship then becoming very slightly non-linear for higher voltages. At 32° C., it will be noted that there is

practically perfect linearity between deflection and voltage up to voltages as great as 500. The merit of a linear relationship will perhaps be understood better by realizing that in terms of operation, it means that if a voltage of 100 volts produces 3 units deflection, then a voltage of 500 volts will produce a deflection five times as great, or 15 units of deflection. Conversely, if the recording pen is deflected 3 units by an applied voltage of 100 volts, and is deflected 15 units by a second applied voltage of unknown value, the operator knows that the second applied voltage is five times as great, or is 500 volts. On the other hand, if the device is being operated at a temperature at which the relationship between deflection and voltage is non-linear, the operator must refer all deflections to a calibration curve in order to determine what voltage corresponds to a given deflection. In short, with a linear relationship, the record produced on the moving paper may be read and understood directly; whereas with a non-linear relationship, the record must, in effect, be translated.

The effect on creep of operation at temperatures above the upper Curie point may be understood by comparing Figs. 9 and 10 with Fig. 8. As indicated above, the phenomenon of creep occurs predominantly at temperatures below the upper Curie point and may be substantially avoided by operating the piezoelectric unit at temperatures above the Curie point. This state of facts is shown by Figs. 8, 9, and 10 which are the graphical records produced by the pen recording device at different temperatures when the voltage which is applied to the device has the characteristics illustrated by Fig. 7. In this latter figure, the horizontal axis corresponds to zero voltage, projections above the axis representing voltages of one sign, for example, positive, while projections below the axis represent voltages of the opposite sign, or negative. Time is measured horizontally along the axis. Fig. 7 shows that, starting from the left end, no voltage was applied to the device for a period of time extending to point K. At that moment the voltage was increased almost instantaneously to a positive value represented by the length of vertical line K-L. This value of voltage was then maintained for the time interval corresponding to the length of the horizontal line L-M, when it was reduced almost instantaneously to zero. No voltage was applied to the device for the time interval represented by the horizontal distance N-P, but at the moment designated by letter P, the voltage was decreased almost instantaneously to the negative value represented by vertical line P-Q. This negative value of voltage was maintained constant for the time interval Q-R and then increased to zero, no voltage being applied for the time interval S-T. A similar series of voltage changes was then applied, the time intervals U-V, W-X, and Y-Z being somewhat shorter in the latter series than their corresponding intervals L-M, N-P, and Q-R in the first series.

Fig. 8 represents the type of record obtained from the pen recording device when the temperature of the device as a whole lies below the upper Curie point and remains constant throughout the duration of the test, the damping unit D having been adjusted for optimum damping at the particular temperature of the test. The curve shown in the figure was obtained at a measured temperature of about 15° C. It will be seen that the record obtained under these con-

ditions is far from being a duplicate of the curve shown in Fig. 7, various portions which should contain sharp corners being rounded off. This rounding-off represents the effect of creep. Again following the curve from the left end, it will be seen that when the voltage was suddenly increased from K to L, the pen point did not move a corresponding amount all at once. Instead it moved rapidly from K' to L' under the influence of the sudden change of applied voltage, but then crept upward to larger deflections during the time interval L-M, this creeping action appearing in Fig. 8 as the asymptotically curved portion L'-M'. At the moment M, when the voltage was suddenly reduced from M to N, the pen point again executed the same type of motion but in the reverse direction, moving quickly under the influence of the sudden voltage reduction from M' to N' and then gradually creeping toward the horizontal axis. The negative voltage cycle P-Q-R-S produces a similar type of response in the pen, the curve P'-Q'-R'-S'-T' being an inverted reflection of the positive voltage cycle K'-L'-M'-N'-P'. Under the influence of the series of voltage changes designated T-U-V-W-X-Y-Z, pen again executed similar motions wherein creep caused rounding of the corners, the difference being that in this series of changes, the time intervals between succeeding changes were short enough to prevent the pen from creeping to the full value of deflection which it would otherwise reach. This is shown in the record at the point X', where it will be seen that the chart is displaced slightly from the axis instead of lying on the axis as it did in the first series at the point P'.

The curve of Fig. 9 was obtained from the same device used in the test of Fig. 8, after it had been warmed from 15° C. to above the Curie point, its actual temperature being about 32° C. In this test the damping unit was left in its previous adjustment which, as indicated above, produced optimum damping at about 15° C. It will be understood that since the damping unit contains material whose properties vary with temperature, the adjustment for optimum damping at the temperature used in the test of Fig. 8 will no longer be the adjustment which produces optimum damping at the higher temperature used in this test. This fact is illustrated partly in Fig. 9, where the improper adjustment of the damping unit is reflected by the "overshoot" and train of vibrations occurring at each of the points L'', N'', Q'', S'', U'', W'' and Y''. It will be understood that the damping unit, being out of adjustment for the higher temperature, no longer absorbs enough energy from the vibrating pen system to prevent it from travelling beyond the true deflection corresponding to the applied voltage K-L. The unabsorbed energy carries the pen beyond this true deflection, and then as the excess energy is gradually absorbed, the pen executes a series of diminishing vibrations and ultimately comes to rest at the true value of deflection represented by the horizontal portion following each of the areas of "overshoot."

Disregarding the overshoot areas of the curve in Fig. 9 it will be observed that there are no asymptotically curved portions characteristic of creep such as appear in Fig. 8. The higher operating temperature has been effective in eliminating these effects of the creep phenomenon. This will be more apparent in Fig. 10, where the overshoot portions have been eliminated by re-

adjusting the damping unit to produce optimum damping at the higher temperature, the test being otherwise conducted under the same conditions which prevailed in the test of Fig. 9. It will be seen from the curve of Fig. 10 that the pen can be caused faithfully to follow the voltage changes of Fig. 7, the rounding-off due to creep having been eliminated by operation at the higher temperature, so that the record obtained from the device is an accurate chart of the voltages applied to the device.

As indicated above, the results shown in Fig. 10 were obtained by operating the device of Figs. 1 through 3 at a temperature of about 32° C. The same kind of results may be obtained over quite a range of temperatures, however. Temperatures between about 30° C. and 45° C. are preferred, particularly since the sensitivity curve within this range is linear, and since the sensitivity undergoes only slight variation with temperature. It should be understood, however, from what has been said above, that temperatures below 30° C., but above the Curie point, may also produce the same kind, but a lesser degree, of the improvements in operation which form the basis of this invention, since by heating the piezoelectric material to only slightly above the Curie point, creep and hysteresis may be markedly reduced, linearity may be materially improved, and impedance variations may be minimized. It will be understood that the piezoelectric unit should not be heated to a temperature high enough to destroy its piezoelectric properties. For Rochelle salt the upper limit is about 55° C.

A further advantage of the heated piezoelectric unit which is of importance mainly in connection with piezoelectric motor devices is the overload protection that is possible with suitably designed circuits. For an uncontrolled piezoelectric device the sensitivity and electrical impedance of the piezoelectric unit will vary with temperature to a marked extent, as pointed out above. In general, an amplifier or other source of signal for an uncontrolled piezoelectric device must have an available output which is several times the output necessary for operation at room temperatures in order that there will be enough output for operation at high temperatures. At room temperature, the impedance of the piezoelectric device is relatively low, and consequently the impedance of the amplifier or other source must also be relatively low so that satisfactory high frequency response may be obtained. Normally the output of the amplifier is adjusted to a satisfactory value for the temperature at the time of operation. However, if the output control of the low impedance source is accidentally turned on full when the piezoelectric unit is at room temperature, the excessive output may very likely damage the piezoelectric unit. All of this high output is necessary, however, when the piezoelectric unit has a higher temperature.

On the other hand, a piezoelectric unit heated to about 30° C. or higher when in operation has a much higher impedance than at room temperature, and the sensitivity is greatly reduced. The amplifier or other source for the heated piezoelectric unit may be designed to supply enough output to operate the unit satisfactorily at its heated temperature, but not much more, so that there is no danger of damaging the unit during normal operation. Due to the relatively high impedance of the unit at its operating temperature, the amplifier may also have a relatively high impedance. Now if the output control of

the amplifier is accidentally turned on full before the unit has been heated to its operating temperature, the amplifier will tend to supply a damaging output, but since the crystal impedance at such temperature is relatively low, and the amplifier impedance is relatively high, only a fraction of the normally-available output will be delivered to the piezoelectric unit, the remainder appearing across the internal impedance of the amplifier, and the piezoelectric unit is thus protected from damage due to excessive voltage. The frequency versus amplitude characteristic will not be correct at low temperatures, but since the device is intended for use only when heated, this is of no consequence.

By way of example, reference is made to Fig. 11, in which 51 is a vacuum tube, 52 is a plate supply battery, 53 is a plate coupling resistor, 54 is the piezoelectric unit, and 55 is a blocking condenser to prevent application of a D. C. bias to the piezoelectric unit. The impedance of the piezoelectric unit at one frequency may be 160,000 ohms at 30° C., and 80,000 ohms at 23° C. Two hundred volts may be required for satisfactory operation of the piezoelectric device at 30° C., and only 50 volts at 23° C. At 30° C. 800 volts may produce the maximum safe displacement of the unit, and at 23° C. 200 volts may produce the maximum safe displacement. If the plate resistance of the vacuum tube is 200,000 ohms, and the coupling resistance 53 is 200,000 ohms, the effective source resistance R' will be 100,000 ohms. The vacuum tube 51 and plate supply battery 52 may be so chosen that the maximum effective generated voltage in series with R' will be about 300 volts. The maximum voltage available across the piezoelectric unit, assuming its impedance x to be that of a pure capacity, will be

$$300 \frac{x}{\sqrt{x^2 + 100,000^2}}$$

Thus at 30° C. the maximum available voltage at the piezoelectric terminals will be

$$300 \frac{160,000}{\sqrt{160,000^2 + 100,000^2}} = 250$$

or a little more than necessary for satisfactory operation, but not enough to damage the unit; and at 23° C., the maximum available voltage at the piezoelectric unit terminals is

$$300 \frac{80,000}{\sqrt{80,000^2 + 100,000^2}} = 187$$

which is more than necessary for satisfactory operation, but not enough to damage the unit.

On the other hand, if the amplifier had an effective impedance of, for instance, 10,000 ohms instead of 100,000 ohms, nearly the full 300 volts could be applied to the piezoelectric unit, and this would be sufficient to damage the unit at room temperature.

As indicated in the preceding paragraphs, changes in temperature not only affect the properties of the piezoelectric unit, but also affect the properties of damping materials sufficiently to produce undesirable alterations in their performance. It consequently is advantageous to stabilize the damping characteristics of a unit by heating it to temperatures in excess of any to which it might be subjected while in operation. This may be accomplished in the manner shown in the device of Figs. 1 to 3 where a common source of heat is provided for the piezoelectric unit A and the tuned damping unit D, or it may be accomplished by providing a separate ther-

mostatically controlled source of heat for the damping unit. It will be apparent, of course, that thermostatic control is generally desirable as a means for holding the temperature of the damping unit within relatively narrow limits at the desired temperature level, and in view of what has been said above, it will be recognized that such control is especially desirable in connection with tuned or frequency selective devices which, by their nature, are easily thrown out of adjustment by temperature variations. It will also be understood, however, that thermostatic control over the temperature of the damping unit or the piezoelectric unit may be omitted under some conditions, since if the device is being operated under conditions which favor a constant rate of heat loss from the device, then the heating units, or the heating circuit, or both, may be designed so that with continuous operation, just enough heat is supplied to hold the temperature of the damping unit or piezoelectric unit at the desired level.

Various applications of the basic features of the invention as disclosed above will be apparent to those skilled in the art, it being obvious that the benefits to be derived from the use of a heated piezoelectric unit either with or without heated damping means may be secured in whole or in part in numerous vibratory devices wherein the piezoelectric unit is operated either as a motor or as a generator. Furthermore, it will be apparent that while the principles underlying the invention are applicable particularly to Rochelle salt units, they are equally applicable to other materials of similar nature which exhibit one or more characteristics of the type disclosed herein. Reference is made especially to the rather extensive class of tartrates which are isomorphous with Rochelle salt. Having now disclosed our invention, what we claim is:

1. A piezoelectric transducer including in combination a vibratory mechanical system coupled to an artificially heated piezoelectric unit containing piezoelectric material having substantially the properties of Rochelle salt, said unit having when in operation a temperature above the upper Curie point of said piezoelectric material and below the temperature at which said material becomes piezoelectrically inoperative.

2. A piezoelectric transducer as claimed in claim 1 which includes artificially heated damping means embodying material whose damping properties vary with temperature, said damping means having, when in operation, a temperature above the ambient room temperature.

3. A piezoelectric transducer as claimed in claim 1 wherein said piezoelectric unit contains Rochelle salt, and its temperature when in operation is between 30° C. and 45° C.

4. A piezoelectric transducer as claimed in claim 1 wherein said piezoelectric unit contains Rochelle salt, and its temperature when in operation is around 30° C.

5. A piezoelectric transducer including in combination, a vibratory mechanical system, an artificially heated piezoelectric unit containing Rochelle salt, and artificially heated mechanical damping means containing damping material whose damping properties vary with temperature, said piezoelectric unit when in operation having a temperature between 30° C. and 45° C., and said damping means, when in operation, having a temperature above the ambient room temperature.

75 6. The method of improving the operating

characteristics of a piezoelectric transducer which includes as elements thereof in combination a vibratory mechanical member coupled to a piezoelectric unit which contains piezoelectric material having substantially the properties of Rochelle salt, said method comprising the step of operating said unit at a temperature above the upper Curie point of said piezoelectric material and below the temperature at which said piezoelectric material becomes piezoelectrically inoperative.

7. The method as claimed in claim 6, wherein said piezoelectric material is Rochelle salt, and said temperature is between about 30° C. and about 45° C.

8. In a piezoelectric transducer, the combination of a vibratory mechanical system, a piezoelectric unit coupled to said system, said piezoelectric unit containing piezoelectric material having substantially the characteristics of Rochelle salt, electrical heating means adapted to supply heat to said unit, and temperature-responsive means adapted to control said heating means to maintain the temperature of said unit above the upper Curie point of said piezoelectric material.

9. In combination, a piezoelectric unit comprising piezoelectric material having substantially the characteristics of Rochelle salt, a member coupled to said piezoelectric unit and adapted to be vibrated thereby, frequency-selective damping means coupled to said member and adapted to dissipate excess energy therefrom at selected frequencies of vibration, heating means adapted to supply heat to said piezoelectric unit and damping means, and temperature-responsive means adapted to control said heating means to maintain the temperature of said unit above the upper Curie point of said piezoelectric material, and to maintain the temperature of said damping means at least above the ambient room temperature.

10. In a piezoelectric transducer, the combination of a vibratory mechanical system, a piezoelectric unit coupled to said system, said piezoelectric unit containing piezoelectric material having substantially the characteristics of Rochelle salt, a pair of electric heating units disposed in heat exchange relationship adjacent opposite faces of the piezoelectric unit, and thermostatic means disposed in the vicinity of one of said heating units and adapted to control said heating means to maintain the temperature of said piezoelectric unit above the upper Curie point of said piezoelectric material.

11. In combination, a piezoelectric unit comprising piezoelectric material having substantially the properties of Rochelle salt, a vibratory mechanical member coupled to said piezoelectric unit to produce an electro-mechanical system adapted to interconvert electrical and mechanical vibratory energy, and means for heating said piezoelectric unit to above the upper Curie point of its said piezoelectric material and below the temperature at which the material loses its piezoelectric properties.

12. In combination, a piezoelectric unit comprising piezoelectric material having substan-

tially the characteristics of Rochelle salt, a mechanical vibratory member coupled to said piezoelectric unit to produce an electro-mechanical system adapted to interconvert vibratory electrical and mechanical energy, damping means associated with said system and adapted to absorb energy therefrom, and heating means adapted to heat said piezoelectric unit and damping means to above the upper Curie point of said piezoelectric material.

13. The combination as claimed in claim 12 including temperature-responsive means for controlling said heating means to maintain the temperature of said piezoelectric unit above the ambient temperature and above the upper Curie point, but not in excess of the temperature at which the piezoelectric material loses its piezoelectric properties, and to maintain the temperature of said damping means above the ambient temperature.

14. Piezoelectric apparatus comprising a piezoelectric unit having greater length and width than thickness and operatively supported in housing means therefor, a pair of electrical heating units supported by said housing means and

25 disposed on opposite sides of said unit adjacent its faces of greatest area, a vibratory member supported on said housing means adjacent one of said heating units and operatively coupled to said piezoelectric unit to be energized thereby, mechanical damping means coupled to said member and adapted to absorb energy therefrom, casing means adapted to enclose said member and damping means, thermostatic means disposed within said casing means adjacent the said damping means and adapted to control said heating units to maintain the temperature of said damping means above the ambient room temperature and to maintain the temperature of the piezoelectric unit above the upper Curie point of its piezoelectric material but below the temperature at which said material becomes piezoelectrically inactive.

15. In combination, a piezoelectrically-actuated vibratory system comprising an artificially heated piezoelectric unit containing piezoelectric material having substantially the characteristics of Rochelle salt, said unit being at a temperature above the upper Curie point when in operation, a signal source energizing said piezoelectric unit and incapable of overloading said unit at the operating temperature, the impedance of said source being sufficiently high to prevent overloading of said unit at temperatures below said operating temperature.

16. In a piezoelectric device, the combination of: a piezoelectric unit comprising piezoelectric material having substantially the properties of Rochelle salt; a vibratory mechanical member coupled to said piezoelectric unit; and means for heating said piezoelectric unit to above the upper Curie point of its said piezoelectric material and below the temperature at which the material loses its piezoelectric properties.
